(57) **CLAIM**

I claim the ornamental design for a decorative magnet, as shown and described.

DESCRIPTION

FIG. 1 is a perspective view of a decorative magnet; and, FIG. 2 is a front elevational view of the decorative magnet. The rear of the decorative magnet is flat and unornamented and forms no part of the claimed design. The broken line showing is included for the purpose of illustrating portions of the article and forms no part of the claimed design.
